UNITED STATES PATENT OFFICE.

ARTHUR BURDELL, OF ATLANTA, GEORGIA, ASSIGNOR, BY MESNE ASSIGNMENTS, TO
A. S. GILMAN, OF CLEVELAND, OHIO.

DUPPLICATING DEVICE.

Application filed July 5, 1924, Serial No. 724,443. Renewed December 10, 1926.

Generically, this invention relates to duplicating devices, but it more especially comprehends the type adaptable for use in connection with a continuous sheet of stationery 5 folded from alternate sides, bearing suitable perforations, so that by writing on the original, a number of duplicates may be provided.

An important object of this invention is 10 the provision of a duplicating device of the above character including novel carbon holding means, said means embodying a plurality of detachable fingers, each finger provided with means for securing a sheet of 15 carbon thereto, and adapted for insertion from opposite sides of the device, between the folds of a sheet of stationery, folded alternately upon itself along its longitudinal edges, the said holding means being adjust- 20 ably movable, longitudinally of the device, so that fresh portions of the inter-leaved carbon sheets may be brought into duplicating position as desired.

Another important object of this invention 25 is the provision of a duplicating device including a novel adjustable means for guiding and clamping the free ends of the stationery, formed with a cutting or tearing edge, and additional delivery or lifting 30 means cooperating therewith, the said clamp- ing and elevating means being simultaneously operable to respectively release and elevate free ends of the stationery so that same may be easily grasped for removal 35 from the device.

A further object of this invention is the 40 provision of a duplicating device embodying a receptacle for containing the folded stationery from which the same may be fed as desired, and adapted to conceal the working parts, and in which may be stored additional stationery for use as desired.

With these and other objects in view, 45 which will become apparent as the description proceeds, the invention resides in the construction, combination and arrangement of parts, hereinafter more fully described and claimed, and illustrated in the accompanying drawings in which like characters of reference indicate like parts throughout the several figures, of which:

Fig. 1 is a perspective view of my im- 50 proved duplicating device;

Fig. 2 is a vertical longitudinal sectional 55 view therethrough;

Fig. 3 is a transverse vertical section on the line 3—3 of Fig. 1.

Fig. 4 is a detailed section showing the 60 operation of the paper lifter;

Fig. 5 is a bottom plan view of the cover; 65

Fig. 6 is a sectional view taken on line 6—6 of Fig. 1; and,

Fig. 7 is an enlarged detailed sectional 70 view of the carbon holding mechanism, taken on line 7—7 of Fig. 1.

I am aware that there are many duplicating devices of various types in use, but none of these so far as I know have proven satisfactory or susceptible of use in connection with all forms of duplication stationery, especially the type known as fan fold form, which is an endless strip folded upon itself alternately from opposite sides, and it was to produce a device embodying novel carbon holding means expediting the insertion of 75 individual carbon sheets from either side of the device, the unitary carbon holding structure being susceptible of longitudinal movement with respect to the device, novel stationery guiding, clamping, cutting and 80 lifting structure, as well as to improve generically duplicating devices heretofore in use, that I evolved the particular type of duplicating device forming the subject matter of this invention.

In the illustrated embodiment characterizing this invention, there is shown a body or cabinet 1 rectangular in configuration and having a cover 2, hingedly secured to one end of the cabinet in any suitable manner.

The rearwardly extending hinge supports 4 are secured to each side of the cabinet flush with its upper edge and adapted for pivotal connection with the brackets 5 which are secured at their inner ends to the under 90 surface of the cover 2, and are formed at their outer ends with upstanding tips 6 adapted to support and provide bearings for the end roller 7.

Suitably secured to the upper surface of 130 the cover 2 spaced from either side are the longitudinal metal strips 8 adapted to support and provide a track for the movable carbon holding structure A embodying a bar 9 slidably supported by the track members 8 105 and formed with the downwardly projecting guide flanges 10. Mounted on each end of bar 9 suitably secured thereto or formed integral therewith are the carbon finger supporting blocks 11 and 12 respectively, one 110

half of the surface of each block being higher than the other half to support the carbon fingers 12 at different levels. The supporting surfaces of block 12 are in a 5 different plane from those of block 11 so that when the fingers 13 are operatively positioned on the said blocks 11 and 12 they will extend respectively in alternate and substantial superposed relation. The said carbon 10 fingers being identical, for convenience in description only one will be described in detail. The finger 13 comprises a thin metal strip to which is pivotally secured a carbon clamping member 14 by lifting knob 15. 15 Said clamping member is folded upon itself to embrace both sides of said strip and one of its sides is provided with a plurality of indentations to firmly contact the carbon sheet with the strip when the clamping 20 member is brought to operative position. The fingers 13 are formed with the diagonally positioned lugs 16 directly under the lifting knobs 15 which are adapted for insertion in corresponding apertures in the surface 25 of the blocks 11 and 12 and the said lifting knobs 15 are adapted to serve as operating means for attaching and detaching the said fingers from the said blocks.

The bar 9 is provided with a depending 30 rod or bolt 17 with its lower extremity terminating in an internally threaded traveler block 18 designed for movement in the longitudinal slot 19 of the cover 2, and adapted to receive the screw 20 positioned directly beneath slot 19 and secured to the under surface of the cover by supporting and bearing plates 21. In order to provide a proper writing surface, the cover 2 slopes downwardly from a point substantially coincident with the screw 20 as at 22, and is provided with a metal writing surface 23.

The extension rod 24 formed with operating knob 25, which extends beyond the end of the cabinet is mounted in supporting 45 bracket 26 with its inner end connected to longitudinal screw 20 by universal joint 27.

Secured to the under surface of the sloping or desk portion of the cover 2 is the centrally positioned supporting member 28 with 50 each end terminating in depending apertured projections 29. Positioned at each side are the aligned brackets 30 terminating in similar depending apertured projections 31. The said portions 29 and 31 are adapted 55 to provide bearings for and support the rods 32 and 33 on each of which is mounted a tension spring 34.

The clamping or knife member 35 is adapted to overlie the lower edge of metallic 60 plate 23 and is formed with downwardly and rearwardly extending arms 36, operable through slots 37 in the cover 2. The said arms being pivotally supported by the outer ends of rods 32 and 33. The free extremities 65 of said arms 36 are apertured to receive the

rod 38 terminating in the upward extension 39 provided with thumb knob 40.

Pivotally mounted on the inner end of rod 32 is the L-shaped member 41 with its outer extremity terminating in an arcuate-like upwardly extending paper lifting or elevating arm 42 and its inner end bifurcated to engage the rod 38.

From the foregoing it is apparent that by 75 depressing the knob 40 the rod 38 will depress the inner ends of arms 36 and member 41 which will simultaneously raise knife member 35 and project upwardly arm 42 thereby elevating the free ends of paper 43 so it can be easily grasped and severed along 80 the edge of member 35.

To operate the device and to facilitate the feed of the paper 43 through the machine it is passed over a roller 44 suspended from the under side of the cover by brackets 45, then over end roller 7 under guide brackets 46 secured to the cover adjacent its rear end and over carbon holder bar 9. The carbon fingers 13 carrying carbon sheets 14' are then 85 inserted between the folds of paper 43 from alternate sides and operatively positioned in the blocks 11 and 12. The folded material is then inserted under guide plates 47 secured to the cover 2 on either side of the plate 23 and under clamping knife 35, whereupon 90 the paper is ready to be written upon and the desired duplication thereby effected.

By operation of the extension rod 24 through the instrumentality of screw 20 and block 18 the carbon holder assembly A is 100 caused to move longitudinally of the device on track members 8 and advancing fresh carbon into duplicating position as desired.

In practice, I have found the form of my 105 invention illustrated in the accompanying drawings and referred to in the above description as the preferred embodiment, is the most efficient and practical; yet realizing the conditions concurrent with the adoption of my device will necessarily vary, I desire to emphasize that various minor changes in details of construction, proportion and arrangement of parts, may be resorted to within the scope of the appended claims without departing from or sacrificing any of the principles of this invention.

Having thus described my invention, and without enumerating variations and equivalents, what I desire protected by Letters Patent is as set forth in the following claims:

1. A duplicating device comprising a cabinet, a cover therefor over which a strip of multi-folded stationery is adapted to pass, a carbon holding means and means coacting therewith for moving the said carbon holding means longitudinally with respect to the said cover, adjustable means for clamping the stationery to the cover, means coacting with the said clamping means for effecting the release of the clamping means and a 130

paper elevating arm simultaneously coacting with said additional means to effect elevation of the free end of the stationery above the surface of the cover.

- 5 2. A duplicating device comprising a cabinet, a cover therefor over which a continuous strip of multi-folded stationery is adapted to pass, carbon holding means longitudinally movable over said cover, said
10 means embodying a plurality of carbon holding fingers detachably supported in alternate planes and insertable between the folds of the stationery alternately from opposite sides of the holder, means including a cutting edge for clamping the end of the stationery to the writing surface, means also carried by the cover for elevating the end of the stationery above the said writing surface, and additional means for effecting release-
15 20 ment of said clamping means with a concomitant operation of the elevating means.
3. A duplicating device comprising a surface over which a strip of multi-folded stationery is adapted to pass, adjustable means
- for clamping the stationery to the surface, means coacting with the said clamping means for effecting the release of the clamping means, and a paper elevating arm, simultaneously coacting with said releasing means to effect elevation of the free end of the stationery above the surface of the cover.
4. A duplicating device comprising a surface over which a strip of multi-folded stationery is adapted to pass, transfer sheets arranged within the folds of the stationery, a carbon-holder for engaging one extremity of the carbon sheets, means operatively associated with the carbon-holder to effect longitudinal adjustment with respect to the stationery, a manually releasable bar normally 40 pressing the stationery against the surface over which it passes, an arcuately movable finger normally positioned beneath said surface and coacting with the manually releasable bar to effect elevation of the stationery simultaneous with the actuation of said clamping bars.

ARTHUR BURDELL.
